CLAIM

The ornamental design for an vehicle wheel center cap, as shown and described.

DESCRIPTION

FIG. 1 is a perspective view of a vehicle wheel center cap embodying my new design;

FIG. 2 is an enlarged front elevational view thereof;

FIG. 3 is an enlarged right side elevational view thereof;

FIG. 4 is an enlarged left side elevational view thereof;

FIG. 5 is an enlarged top plan view thereof; and,

FIG. 6 is an enlarged bottom plan view thereof.

The broken lines shown in FIG. 1 are for illustrative purposes, only, and the subject matter depicted by such broken lines does not constitute any part of the claimed invention.
